UNITED STATES PATENT OFFICE.

HEZEKIAH J. BURNWORTH, OF ZANESVILLE, OHIO.

DESIGN FOR A CHECKREIN-HOLDER.

SPECIFICATION forming part of Design No. 27,811, dated November 2, 1897.

Application filed September 14, 1897. Serial No. 651,682. Term of patent 7 years.

To all whom it may concern:

Be it known that I, HEZEKIAH J. BURNWORTH, a citizen of the United States, residing at Zanesville, in the county of Muskingum and State of Ohio, have invented a certain new and useful Design for Rein-Holders, of which the following is a specification, reference being had therein to the accompanying drawings, in which—

10 Figure 1 is a perspective view of the preferred form of the device, and Fig. 2 a plan view thereof.

The leading feature consists of a flat oblong plate provided at each of its four corners with a depending lug and having extending from one of its ends a tongue or strip which is curled upward over the plate and formed into an open ring, as more fully hereinafter set forth.

Referring to the drawings by letters, *a* designates the flat oblong plate; *b*, the depending ears projecting from the corners of the plate, two projecting from each longitudinal edge, and *c* the strip or tongue projecting from one end of the plate and coiled upward and over the same into an open ring, said strip tapering in width toward its free end and its outer surface being convex in cross-section.

I claim—

The design for a rein-holder substantially as shown and herein described.

In testimony whereof I affix my signature in presence of two witnesses.

HEZEKIAH J. BURNWORTH.
